UNITED STATES PATENT OFFICE.

WILLIAM T. BLOUNT, OF ORRVILLE, OHIO, ASSIGNOR OF ONE-HALF TO WILLIAM G. BARNWELL, OF SAVANNAH, GEORGIA.

DESIGN FOR A SAW HANDLE.

Application filed May 11, 1923. Serial No. 6,140. Term of patent 14 years.

To all whom it may concern:

Be it known that I, WILLIAM T. BLOUNT, a citizen of the United States of America, residing at Orrville, in the county of Wayne and State of Ohio, have invented a new, original, and ornamental Design for a Saw Handle, of which the following is a specification, reference being had to the accompanying drawings, forming a part hereof.

I claim:

The ornamental design for a saw handle as shown.

WILLIAM T. BLOUNT.

Witnesses:

S. M. KIRK,
ELMER J. BEYLER.
